[57] **CLAIM**

The ornamental design for a bag carrying and organizing device, as shown and described.

DESCRIPTION

FIG. 1 is a perspective view of a bag carrying and organizing device showing our novel design in a closed position; FIG. 2 is a perspective view of a bag carrying and organizing device showing our novel design in an open position; FIG. 3 is a right side plan view thereof in a closed position which is symmetrical with and equivalent to a left side plan view;

FIG. 4 is a right side plan view thereof in an open position which is symmetrical with and equivalent to a left side plan view;

FIG. 5 is a front side plan view thereof in a closed position; FIG. 6 is a front side plan view thereof in an open position; FIG. 7 is a rear side plan view thereof in a closed position; and,

FIG. 8 is a rear side plan view thereof in an open position. The bag carrying and organizing device is shown which allows a person to conveniently hold together and carry a number of bags which are typically found at a grocery store. The bag carrying and organizing device is a carrying handle for multiple bags and a retaining device to hold the bag tops together when not used for carrying.
